Primary Examiner — L. A. Grabenstetter(74) *Attorney, Agent, or Firm* — Syncoda LLC; Feng Ma(57) **CLAIM**

The ornamental design for a mobile translator device, as shown and described.

DESCRIPTION

1.-2. Mobile translator device

1.1 : Front

1.2 : Back

1.3 : Left

1.4 : Right

1.5 : Top

1.6 : Bottom

1.7 : Front Perspective

1.8 : Back Perspective

2.1 : Front

2.2 : Back

2.3 : Left

2.4 : Right

2.5 : Top

2.6 : Bottom

2.7 : Front Perspective

2.8 : Back Perspective

1 Claim, 16 Drawing Sheets(56)
